UNITED STATES PATENT OFFICE

BOY W. JOHNSON, OF COLUMBUS, OHIO, ASSIGNOR TO THE JOHN W. BROWN MANUFACTURING COMPANY, OF COLUMBUS, OHIO, A CORPORATION OF OHIO

BULB MOUNTING FOR HEADLAMPS

Application filed May 28, 1929. Serial No. 366,676.

This invention relates to an improved bulb mounting for use in connection with motor vehicle headlamps, and a primary object of the invention resides in the provision of a simple yet efficient mounting for effecting the support of an incandescent bulb in an axial position wherein the filament or filaments of the bulb will occupy a certain predetermined relationship with the parabolical surface of a lamp reflector, to the end of obtaining an efficient projection of light from the lamp and to overcome the evils and annoyances the projection of light from a headlamp into undesired area or zones causes.

It is another object of the invention to provide a mounting wherein the bulb and the filaments thereof are stationarily positioned in relation to the reflector at all times and wherein the use of adjusting devices for varying the focal position of the bulb with respect to the reflector are eliminated.

With these and other objects in view which will appear as the description proceeds, the invention consists in the novel features of construction, combinations of elements and arrangements of parts herein-after to be fully described and pointed out in the appended claims.

30 In the accompanying drawing:

Figure 1 is a vertical sectional view taken through a headlamp provided with the bulb mounting comprising the present invention,

Figure 2 is a rear elevation of the mounting looking toward the axial rear portion of a lamp reflector,

Figure 3 is a vertical longitudinal sectional view taken through the mounting,

Figure 4 is a detail perspective view of the 40 insulated base piece constituting a part of the mounting,

Figure 5 is a perspective view of the outer metallic sleeve portion of the mounting,

Figure 6 is a group view showing in 45 front and side elevation the resilient ring which is employed for maintaining the mounting in place, and

Figure 7 is a fragmentary rear elevation of the lamp reflector.

50 Referring more particularly to the draw-

ing, the numeral 1 designates the body or casing of a headlamp. Within the body there is arranged any standard type of reflector 2, the front of the reflector being closed by means of the usual lens 3. The 55 axial portion of the reflector is provided with an opening 4 which is adapted to receive a mounting 5 for effecting the support of an incandescent lamp bulb 6 within the reflector 2 and in a required position in 60 relation to the reflecting surfaces of said reflector so as to secure a predetermined projection of light from the lamp.

The mounting 5, which comprises the present invention, consists of a metallic 65 sleeve 7 which, in this instance, has been formed intermediately of its end to provide an annular rib 8. This rib serves as a positioning means and engages with that portion of the reflector surrounding the opening 4, thus limiting the axial movement of the sleeve in a rearward direction. Arranged in one end of the sleeve 7 is a base element 9 formed from any suitable dielectric substance. This base is loosely mounted in the 70 sleeve but is positively retained in a desired position by means of a pair of fingers or tongues 10 which are integrally formed with one end of the sleeve and which, following insertion of the base into its operative position, are bent inwardly so as to retain the base against movement. The 75 insertive movement of the base is also limited by means of a stop lug 11 which is punched inwardly from the outer wall of the sleeve 80 so as to engage within a recess 12 provided in the base 9. Not only does the lug 11 serve to limit the forward movement of the base 9 in the sleeve but it also serves to position the base in a certain axial location.

This is required due to the fact that the base 9 has connected therewith a pair of plungers 13 which act as current conductors and are adapted to be connected with the wires 14 which are employed to transmit current to the filament of the bulb 6. These plungers are arranged in parallel order within the base 9 and have their forward ends provided with heads 15 with which engage coil springs 16, the springs 100

- 16 being disposed between the heads 15 and the forward wall of the base 9 so as to normally support the plungers 13 outwardly. The heads 15 are adapted for registration 5 and contact with the customary spaced and stationary contacts 17 provided on the rear of the bulb base 6. The contacts 17 are, of course, connected with the filaments 18 of the bulb in the usual manner.
- 10 The base of the bulb is provided with the customary pins 19 which are adapted to be positioned within bayonet slots 20 formed in the forward end of the sleeve 7. Surrounding the sleeve 7 is a flat corrugated spring washer 21. This washer has 15 been shown particularly in Figure 6. In practice the washer is positioned between the outturned lugs 22 formed with the sleeve 7 and the rear wall of the reflector 2, the 20 said washer serving to resiliently maintain yet positively position the rib 8 in contact with its seated portion around the opening 4. The inner edge of the washer 21 is formed with a plurality of recesses 23 by 25 means of which the washer may be brought into registration with the lugs 22 to effect the removal of the washer from the sleeve and the consequent dissembling from the reflector. Likewise, the reflector 2 has the 30 edge of the axial opening 4 provided with recesses 24 through which the lugs 22 are passed during the positioning of the sleeve 7 within the reflector. One of the recesses 24 is of greater width, as indicated at 24', 35 in order to receive the lug 25 also formed with the sleeve 7. By forming the lug 25 and one of the recesses 24 of greater width, it will be seen that the sleeve 7 can only be inserted within the reflector one way and 40 will then be maintained in a certain axial location with respect to the reflector. The outer peripheral edge of the washer is also notched as at 26 to permit of the insertion of a tool (not shown) for effecting the rotation 45 of the washer when the latter is in its applied position and to register the depressions 27 of the spring washer 21 with the lugs 22 of the sleeve 7. Thus the washer is held in firm contact with the sleeve 7 and 50 the reflector 2 and also prevents accidental rotation thereof.
- In view of the foregoing it will be seen 55 that the present invention provides a mounting of a formation permitting of its economical manufacture and convenient assembly. The relatively movable or separable parts of the mounting are securely related both by positive and resilient fastening means so 60 that the device will securely maintain its position and overcome looseness, rattle and vibration. The filaments of the bulb occupy, through the provision of the mounting, a certain focal relationship to the reflector 65 and maintain this relationship constant throughout the use of the lamp.

What is claimed is:—

1. The combination with a reflector provided with an opening, of a tubular lamp holder occupying said opening and formed with an annular shoulder engaging one side 70 of the reflector, a plurality of lugs struck out from said holder at a point spaced from said shoulder and the other side of the reflector, a corrugated spring washer on said holder positioned between said lugs and reflector, said washer being formed with notches in the corrugations nearest the reflector and along its inner periphery and through which said lugs pass, there being depressions formed in the corrugations 80 farthest away from said reflector whereby upon the rotation of said washer said lugs will ride up on the corrugations and be seated within the depressions, the washer serving to draw the shoulder of said holder into 85 firm holding engagement with said reflector.

2. The combination with a reflector provided with an opening, of a tubular lamp holder extending through said opening and formed with an annular bead engaging one 90 side of the reflector, a plurality of lugs struck out from said holder at a point spaced from said bead and the other side of the reflector, a corrugated spring washer on said holder positioned between said lugs and reflector, said washer being formed with notches in the corrugations nearest the reflector and along the inner periphery of said washer, depressions formed in the corrugations farthest away from said reflector, and 100 notches formed in the latter corrugations for the insertion of a washer rotating tool whereby during the positioning of said washer upon said holder said lugs will pass through the inner notches and engage with 105 the washer so as to draw the same towards said reflector.

In testimony whereof I affix my signature.
ROY W. JOHNSON.
